US0D1055589S

(12) **United States Design Patent** (10) **Patent No.:** **US D1,055,589 S**
(45) **Date of Patent:** **** Dec. 31, 2024**

(54) **SHOE RACK**

(71) Applicant: **Yongli Zhou**, Zhejiang (CN)

(72) Inventor: **Yongli Zhou**, Zhejiang (CN)

(**) Term: **15 Years**

(21) Appl. No.: **29/817,163**

(22) Filed: **Nov. 29, 2021**

(51) **LOC (14) Cl. 06-04**

(52) **U.S. Cl.**

USPC **D6/675.2; D6/681.2**

(58) **Field of Classification Search**

USPC D6/664, 672, 673, 675, 675.1, 675.2, D6/675.3, 675.5, 680.2, 681, 681.2, 683,

D6/683.1

CPC A47B 47/00; A47B 47/0083; A47B 96/02; A47F 5/0018; A47F 7/08

(57) **CLAIM**

The ornamental design for a shoe rack, as shown and described.

DESCRIPTION

FIG. 1 is a front and top perspective view of a first embodiment of a shoe rack design showing my new design. FIG. 2 is a rear and bottom perspective view of a first embodiment of a shoe rack.

FIG. 3 is a front view of a first embodiment of a shoe rack.

FIG. 4 is a rear view of a first embodiment of a shoe rack.

FIG. 5 is a left side view of a first embodiment of a shoe rack.

FIG. 6 is a right side view of a first embodiment of a shoe rack.

FIG. 7 is a top view of a first embodiment of a shoe rack.

FIG. 8 is a bottom view of a first embodiment of a shoe rack.

FIG. 9 is a front and top perspective view of a second embodiment of a shoe rack.

FIG. 10 is a front view of a second embodiment of a shoe rack.

FIG. 11 is a rear view of a second embodiment of a shoe rack.

FIG. 12 is a left side view of a second embodiment of a shoe rack.

FIG. 13 is a right side view of a second embodiment of a shoe rack.

FIG. 14 is a top view of a second embodiment of a shoe rack; and,

FIG. 15 is a bottom view of a second embodiment of a shoe rack.
